GLOW DISCHARGE CATHODE HAVING A LARGE ELECTRON BEAM EMITTING APERTURE

Fernand J. Ferreira, Hazardville, Conn., assignor to United Aircraft Corporation, East Hartford, Conn., a corporation of Delaware

Filed Nov. 17, 1965, Ser. No. 508,302
12 Claims. (Cl. 313—207)**ABSTRACT OF THE DISCLOSURE**

A large apertured hollow cathode is described for producing a collimated beam of electrons and wherein the aperture is either equal or larger than the cathode fall or bears a predetermined relationship to the entire frontal beam emitting surface of the cathode.

Conventional means for producing electron beams involve the liberation of electrons from the surface of a heated cathode by thermionic emission. Recently, electron beams have been produced from a narrow apertured glow discharge hollow cathode as a result of the volume production of electrons within a hollow chamber enclosed by the cathode. In glow discharge devices various operating modes may be encountered if one, for instance, varies the potential difference between the cathode and the anode and the gas density of the environment. One of these modes produces a well-defined electron beam which may predictably and advantageously be used to work materials. Other modes such as the arc mode also is a good source of electrons but this mode exhibits erratic behavior and does not produce a high energy beam.

These narrow apertured hollow cathodes have hollow chambers fabricated from a wire mesh or solid metal with a single aperture in one end. When the cathode is subjected to a high negative potential with respect to an anode and with the proper cathode geometry and pressure level in the hollow chamber, a well-defined pencil beam of high current density, high energy electrons emanate from the aperture. An example of the versatility of the configurations possible with the apertured hollow cathode may be found in my copending application Ser. No. 417,399, filed Dec. 10, 1964, entitled "Annular Hollow Cathode Discharge Apparatus" and assigned to the same assignee.

The hollow cathode has a cathode fall region adjacent its external surface. The electrons for the beam are obtained, however, from a plasma generated by an intense discharge within the chamber enclosed by the cathode. If the aperture through which the electron beam emerges is then so shaped to where at least one cross-sectional dimension is less than the size of the cathode fall region, an electrostatic focussing effect on the electrons is obtained and a well-defined beam is produced.

The range of gas densities and voltages in which this narrow apertured hollow cathode operates with stability with little tendency to enter the arc mode is generally small. For instance, an apertured cathode operating in argon at 24 microns of mercury pressure must operate at 1200 volts potential and will enter the arc mode if the potential is raised to 2000 volts or the pressure is increased to 40 microns. At about 7 microns of pressure, a potential of 10,000 volts can be used but an increase in the pressure to 10 microns will result in an arc mode. Hence, with each particular gas density necessary for an electron beam mode, there is a maximum voltage at which a relatively small increase in gas density will shift the operation into the arc mode.

2

A particular operating regime cannot be easily defined for the narrow apertured hollow cathode since this depends upon many factors such as type of gas used, the density of the gas, operating voltage, geometric shape of the cathode, beam power requirements, stability, and where the anode is close to the cathode the cathode-to-anode spacing, etc. Nevertheless, it can be stated with reasonable accuracy that its operation for most useful applications involves gas pressures of about 50 microns of mercury or less. For high voltage applications of greater than 20 kv., much lower pressure regimes of the order of 10 microns or less are required and are subject to instability with relatively small excursions in the gas pressure due to outgassing or other factors. Narrow apertured hollow cathodes have been operated in the electron beam mode at high pressures but their dimensions are then so small as to seriously limit the power levels below practical utility for most electron beam applications.

The many useful functions to which electron beams may be put are illustrated for instance by the patents to Steigerwald 2,987,610 directed at deep penetration of materials and Patent No. 2,902,583 directed to pulsed electron beam working of materials. To achieve the deep penetration, the power density of the beam at the workpiece must be sufficiently high. In the event conventional welding, a surface electron beam working technique, is used, sufficient power is needed to heat and melt an area on the surface of the workpiece with subsequent fusion at deeper levels in the material occurring by the conduction of the heat from the surface.

As a result of working of materials with an electron beam, a substantial amount of outgassing and evaporation from the workpiece occurs. This causes excursions from a mean pressure level of the gas and increases the probability of arcing in the apertured hollow cathode. Furthermore, temperature variations of the gas cause excursions in its density and further reduces the stability of the operation. In practical applications these factors have made high voltage operation of about 15,000 volts highly unstable with an increase in the pressure of several microns causing an arc mode and a comparable decrease causing extinguishment of the discharge. In fact, complicated and expensive closed loop gas pressure controls have been found necessary to maintain the electron beam from an apertured hollow cathode. These disadvantages have been overcome with a newly developed glow discharge cathode.

Accordingly, it is an object of this invention to provide a glow discharge device for producing an electron beam at high pressure levels.

It is a further object of this invention to provide a glow discharge device operating in a gaseous environment for producing an electron beam the stability of which is insensitive to excursions in the density of the gas.

Across a region, called the cathode fall, and adjacent the cathode, most of the potential drop existing between the cathode and anode occurs. In the apertured hollow cathode the aperture has at least one cross-sectional dimension which is less than the cathode fall distance D_c and the beam produced by it is noticeably smaller than the aperture. It has been found however that a stable electron beam can also be produced if the aperture becomes equal or larger at long as the side walls still define a cavity within which the electron beam can be formed. The size of the aperture is characterized by the shape of the electron beam it produces. The shape of the beam having cross-sectional dimensions that are equal or larger than the corresponding aperture dimensions. Although the relatively large aperture size of the cavity reduces the focussing action, the electron beam that emerges from the cavity may be advantageously used for the working of materials.

The large aperture has a dimensional characteristic which has been found to also have a critical relationship with a corresponding dimension of the cathode wall in which it appears. Since the electron beam emitted from such a large apertured device obtains most of its electrons from the plasma in the cavity it is classified as a large apertured hollow cathode.

It is therefore an object of this invention to provide an electron beam from a cathode enclosing a cavity having an aperture where the electron beam has cross-sectional dimensions that are equal or larger than corresponding aperture dimensions.

It is a further object of this invention to provide a device for producing a stable electron beam from a hollow cathode having an aperture in a wall which bears a specific relationship with said wall.

It is still another object of this invention to provide a device for producing an electron beam from a hollow cathode having an aperture of cross-sectional dimensions that are equal or larger than the cathode fall.

These and other objects of this invention will become apparent upon a review of the following description and the accompanying figures wherein:

FIGURE 1 shows a cross-sectional view of a large apertured hollow annular cathode of this invention.

FIGURE 2 shows a prior art narrow apertured hollow cathode.

FIGURE 3 is a side view of a large apertured hollow cathode.

FIGURE 4 illustrates a wide apertured hollow cathode of the single bounding wall type.

FIGURE 5 is an end view of the cathode of FIGURE 4.

FIGURE 6 illustrates an outwardly electron beam radiating hollow cathode of the wide apertured type.

In FIGURE 1 a hollow annular cathode 1 is located in a chamber 3 of which a portion of one of its walls 5 is shown. The chamber 3 is evacuated to the appropriate pressures necessary for establishing an electron beam from the hollow cathode. The cathode 1 has a peripheral rear wall 7 and extending inwardly therefrom two side walls 9 and 11. The side walls 9 and 11 intersect the extremities of rear wall 7 at right angles so that an annular cavity 14 is formed. The cathode 1 has an annular aperture 16 which is formed by the inward ends of walls 9 and 11.

The cathode 1 is annular but other closed circuitous arrangements of the cathode are possible, such as for the working of irregularly shaped workpieces.

Coaxial with the annular cathode is a workpiece 18 which serves an anode and is connected to the positive side of a high voltage source 20. In the event the workpiece 18 is a nonconductor, the positive side of the high voltage power supply may be connected to any large conductive surface within the chamber 3. The negative side of the source 20 is connected to the cathode 1 via the high voltage cable 22 and conductor feedthrough assembly 24. The cathode 1 is supported at several places around its perimeter with nonconductive pin assembly 26. The feedthrough assembly 24 and the pin support assembly 26 may be of the type described in the copending application by Allan P. Walch, entitled, "Mounting for a Glow Discharge Cathode," Ser. No. 508,201, filed Nov. 17, 1965, and assigned to the same assignee.

The cathode 1 is surrounded by a shield 28 to suppress the emission of electrons from the cathode surfaces opposite the shield. The gap between the shield and the cathode is adjusted according to well-known gas pressure scaling laws.

FIGURE 2 shows a prior art narrow apertured hollow cathode 30 without a shield as described in my copending application Ser. No. 417,399. The cathode 30 is provided with an aperture 32 of height A and length L in one wall 34 which has a height H. The length L of the wall 34 and, of course, the whole cathode may vary and form a continuous annular configuration or a straight section. The aperture may be circular if its length L is small in

which case a pencil beam may be produced from the device. The aperture-to-wall ratio of A/H is less than .7 and the aperture has at least one cross-sectional dimension such as A which is less than the cathode fall D_c.

The hollow cathode 1 when charged to the proper potential and exposed to the proper pressure level will produce a well-defined electron beam whose width is approximately that of the aperture 16. The aperture 16, however, must have a predetermined size to establish the stable electron beam. Its dimensions may be characterized by the electron beam-to-aperture size ratios. Since the narrow apertured hollow cathode produces an electron beam whose half power or half-power density profile is smaller than the aperture from which the beam is produced, a substantial change in these profiles is observed with the larger apertures in the hollow cathodes of this invention. With large apertured hollow cathodes, the electron beam half power and half-power density profiles are substantially equal or larger than the aperture and the resultant beam is unexpectedly stable.

The electrons for the beam are produced to a large extent as a result of the trapping effect in the cavity 14. The plasma in this cavity can be made more intense by adding extensions such as 36 and 38 in FIGURE 3 to narrow the aperture 16. There is a well-defined limit, however, to the size of these extensions and this may be determined by the relationship between the A dimension of the aperture and H dimension of the wall in which it appears. Below approximately an A/H ratio of .7

the beam protruding from the cathode is much smaller than the aperture and has the characteristic of prior art narrow apertured hollow cathode electron beams. Above this ratio of .7 the beam produced by the cathode is substantially determined by the size of the aperture and exhibits great stability with varying gas pressures and anode-to-cathode potentials. Gas pressures in excess of 200 microns and at voltages of 10 kilovolts or more may be used to produce an electron beam whose stability is unaffected by voltage variations and gas density excursions. Of course, in cases where there is no aperture wall, the ratio approaches unity but this ratio still produces a stable beam. The aperture 16 is usually also provided with cross-sectional dimensions which are equal or larger than the cathode fall distance D_c. The cathode fall distance encompasses for most applications that distance from the cathode where most of the potential rise from cathode to anode occurs. These distances may be determined experimentally or may be obtained for instance of FIGURE 8.10, p. 229, from the book "Gaseous Conductor" by James Dillon Cabine, a 1958 Dover publication. The cathode fall distance for a cathode operating in helium at a pressure of 500 microns and at 2000 volts is approximately 1 cm.

Having described an annular arrangement, other configurations are possible such as a cylindrical device as in FIGURE 3 where one wall of the cylinder is provided with an aperture whose cross-sectional dimensions meet the criteria of the annular arrangement described above. The aperture-to-wall dimensions cannot fall below .7 if the large stable beam effect is to be maintained.

Another circuitous configuration wherein the electron beam is projected outwardly from the circuitous cathode is possible with this invention and especially suited for electron beam working inside hollow chambers, such as pipes.

Other cathode shapes possible with this invention are described in my copending application Ser. No. 417,399.

It is to be understood that the invention is not limited to the specific embodiment herein illustrated and described but may be used in other ways without departure from its spirit as defined by the following claims.

FIGURE 4 shows a cathode having a single backwall 7' and a single bounding wall 9'. The end view of FIGURE 4 is shown in FIGURE 5 and shows the cylindrical arrangement of the cathode structure therein. A shield 28' is selectively spaced from the cathode structure to

provide the suppression of the glow discharge from the walls enclosed. The aperture 16' of the cathode structure is greater than the cathode fall. The cavity 14' is sufficient to produce the beam of electrons from the hot plasma present therein.

FIGURE 6 illustrates an outwardly radiating annular cathode structure having an inner wall 7 and two bounding walls 9 extending outwardly from the inner wall 7 to define an annular cavity 14 having an aperture 16. The aperture 16, again, is greater than the cathode fall to permit a wide beam of electrons to be emitted from the annular cavity 14.

I claim:

1. A hollow cathode structure operating at a high negative potential with respect to an anode in a gaseous chamber evacuated to a predetermined density range of the gas comprising:

means for establishing a glow discharge and a cathode fall for the production of an electron beam from the cathode structure,

said cathode structure having a peripheral wall, bounding walls extending away from said peripheral wall to define a cavity of sufficient size to establish said glow discharge therein,

said bounding walls further forming an aperture, said aperture having all its cross-sectional dimensions substantially equal or greater than the cathode fall, and

a shield selectively spaced from and enclosing said peripheral and bounding walls, said shield inhibiting the generation of electrons from the enclosed walls.

2. A device as recited in claim 1 and further comprising:

an aperture wall extending from at least one of said bounding walls across the aperture to reduce at least one of the cross-sectional dimensions of said aperture and where the reduced aperture dimensions bears a ratio with respect to the unreduced aperture dimension of greater than .7.

3. A device as recited in claim 1 where said peripheral wall is circuitous and defines two circuitous edges and where the bounding walls extend from said edges.

4. A device as recited in claim 3 where said bounding walls are substantially transverse to said peripheral wall.

5. A hollow cathode structure operating at a high negative potential with respect to an anode in a gaseous chamber evacuated to a predetermined density range of the gas comprising:

a cathode structure having a back wall, a bounding wall extending away from said back wall to form a cavity of sufficient size to establish a glow discharge therein for generation of a beam of electrons,

said bounding wall further forming an opening, said opening having all cross-sectional dimensions equal or greater than the cathode fall, and

a shield selectively spaced from and enclosing said peripheral and bounding walls, said shield inhibiting the flow of electrons from the enclosed walls and enhancing the generation of a beam.

6. A device as recited in claim 5 and further comprising:

an aperture wall extending from said bounding wall across the opening to form an aperture having cross-sectional dimensions smaller than the corresponding dimensions of the opening, and

where said corresponding cross-sectional dimensions of the aperture and the opening bear a respective ratio greater than .7.

7. A hollow cathode structure as recited in claim 1 wherein said

bounding walls extend outwardly from said peripheral wall to define a cavity of sufficient size to establish said glow discharge therein.

8. A hollow cathode structure as recited in claim 1 wherein said

bounding walls extend inwardly from said peripheral wall to define a cavity of sufficient size to establish said glow discharge therein.

9. A hollow cathode structure operating at a high negative potential with respect to an anode in a gaseous chamber evacuated to a predetermined density range of the gas comprising:

means for establishing a glow discharge and a cathode fall for the production of an electron beam from the cathode structure,

said cathode structure having a peripheral wall, bounding walls extending away from said peripheral wall to define a cavity of sufficient size to establish said glow discharge therein,

said bounding walls further forming an opening, an aperture wall extending from at least one of said bounding walls across the opening to form an aperture having a cross-sectional dimension smaller than the corresponding dimension of the opening, where said corresponding cross-sectional dimensions of the aperture and the opening bear a respective ratio greater than .7, and

a shield selectively spaced from and enclosing said peripheral and bounding walls, said shield inhibiting the generation of electrons from the enclosed walls.

10. A hollow cathode structure operating at a high negative potential with respect to an anode in a gaseous chamber evacuated to a predetermined density range of the gas comprising:

means for establishing a glow discharge and a cathode fall for the production of an electron beam from the cathode structure,

said cathode structure having a back wall, a bounding wall extending away from said back wall to form a cavity with said back wall and of sufficient size to establish a glow discharge therein,

said bounding wall further defining an opening, an aperture wall extending from said bounding wall across the opening to form an aperture having cross-sectional dimensions smaller than the corresponding dimensions of the opening, where said corresponding cross-sectional dimensions of the aperture and the opening bear a respective ratio greater than .7, and

a shield selectively spaced from and enclosing said peripheral and bounding walls, said shield inhibiting the generation of electrons from the enclosed walls.

11. A hollow cathode structure having an aperture and operating at a high negative potential with respect to an anode in a gaseous chamber evacuated to a predetermined density range of the gas comprising:

means for establishing a glow discharge and a cathode fall for the production of an electron beam from the cathode structure,

said cathode structure having a peripheral wall, bounding walls extending away from said peripheral wall to define a cavity of sufficient size to establish said glow discharge therein,

said bounding walls further forming an opening opposite said peripheral wall, an aperture wall extending from at least one of said bounding walls across the opening to form an aperture having a width smaller than the corresponding dimension of the opening, where said corresponding width of the aperture and the opening bear a respective ratio greater than .7, and

where the electron beam is characterized by having cross-sectional dimensions that are larger than the corresponding aperture dimensions, and

a shield selectively spaced from and enclosing said peripheral and bounding walls, said shield inhibiting the generation of electrons from the enclosed walls.

12. A hollow cathode structure having an aperture and operating at a high negative potential with respect to an

anode in a gaseous chamber evacuated to a predetermined density range of the gas comprising:
 means for establishing a glow discharge and a cathode fall for the production of an electron beam from the cathode structure,
 said cathode structure having a back wall,
 a bounding wall extending away from said back wall to form a cavity with said back wall and of sufficient size to establish a glow discharge therein,
 said bounding wall further defining an opening opposite said peripheral wall,
 an aperture wall extending from said bounding wall across the opening to form an aperture having a smaller dimension than the corresponding dimensions of the opening,
 where said corresponding smaller dimensions of the aperture and the opening bear a respective ratio greater than .7.

where the electron beam is characterized by having cross-sectional dimensions that are larger than the corresponding aperture dimensions, and
 5 a shield selectively spaced from and enclosing said peripheral and bounding walls, said shield inhibiting the generation of electrons from the enclosed walls.
